UNITED STATES PATENT OFFICE.

ROSWELL A. MOORE, OF WATERBURY, CONNECTICUT, ASSIGNOR TO WATERBURY
BUCKLE CO., OF WATERBURY, CONNECTICUT, A CORPORATION.

BUCKLE.

Application filed November 5, 1923. Serial No. 672,733.

To all whom it may concern:

Be it known that I, Roswell A. Moore, a citizen of the United States, residing at Waterbury, in the county of New Haven and State of Connecticut, have invented a new and useful Improvement in Buckles; and I do hereby declare the following, when taken in connection with the accompanying drawings, and the characters of reference marked thereon, to be a full, clear, and exact description of the same, and which said drawings constitute part of this application, and represent, in—

Fig. 1 a view in front elevation of a rustless buckle constructed in accordance with my invention, shown as applied to a piece of webbing, which is partly broken away.

Fig. 2 an edge view thereof.

Fig. 3 a sectional view on the line 3—3 of Fig. 1.

Fig. 4 a detached, perspective view on an enlarged scale of the wire buckle-frame.

My invention relates to an improvement in rustless buckles of the type shown and described in United States Patent No. 847,811, granted March 19, 1907, on the application of Morris Peller, the object of my present invention being to produce a wire-frame buckle in which the wire of the frame is bent to grip the fixed end of the webbing, whereby an economy of labor and webbing is effected, all sewing of the webbing being eliminated.

With these ends in view, my invention consists in a wire-frame rustless buckle having certain details of construction as will be hereinafter described and pointed out in the claims.

In carrying out my invention, as herein shown, the buckle-frame consists of a single piece of wire bent to form two complementary pintles 5, complementary side-bars 6 and a lower bar 7, from which, at points toward the ends thereof, two integral, upwardly-opening gripping-hooks 8 depend. The said pintles 5 form, in effect, the upper bar of the buckle-frame and serve to pivotally mount a sheet-metal buckle-lever, which consists of a finger-piece 9, a gripping-edge 10 and mounting-fingers 11, which are wrapped around the pintles 5. In webbing my improved buckle, the fixed end 12 of the webbing 13 is inserted into the upwardly-opening hooks 8, which are

then swaged down upon the webbing, so as to firmly grip the same, whereby the webbing is permanently attached to the buckle-frame without resorting to sewing, and with great economy in the amount of it used for this purpose. The webbing 13 is then passed from front to rear, through the webbing-opening 14 of the frame, and then downwardly and upwardly to form the usual loop, and in front of and over the hooks 8 and then from front to rear through the webbing-opening and under the gripping-edge 10 of the buckle-lever, and then upward, as clearly shown in Figs. 2 and 3. In thus threading the buckle, the running portion of the webbing is deflected over and cushioned upon the bend 15 in the webbing formed adjacent to the fixed end 12 of the webbing by passing the same over the lower bar of the frame.

I am aware that it has heretofore been proposed to attach the fixed end of the webbing of a rustless buckle of the Peller type by means of prongs struck out of a sheet-metal buckle-frame, whereby sewing is eliminated. I am also aware that it has been proposed to split the wire of a wire-frame Peller buckle for the attachment of the fixed end of the webbing without sewing. I do not, therefore, broadly claim a rustless buckle of the Peller type, having its frame adapted for the attachment of the fixed end of the webbing, without resorting to sewing, but only a rustless buckle of the Peller type, in which a wire buckle-frame is made of a single piece of wire bent so as to adapt it to grip the fixed end of the webbing.

I claim:

1. In a rustless buckle, the combination with a one-piece wire-frame having its lower bar bent to form a depending, upwardly-opening gripping-hook for the reception of the fixed end of the webbing upon which the hook is clamped, of a buckle-lever pivotally mounted upon the upper portion of the frame, and a piece of webbing having its fixed end inserted downwardly into the said hook, which is clamped upon it and then passed from front to rear over the lower bar of the frame and then downward to form a loop and then in front of the said hook and over the bend of the fixed end of the webbing and then under the gripping-edge of the said lever, and

then upward from front to rear for deflection by the buckle-lever over the loop formed adjacent to the fixed end of the webbing.

- 5 2. In a rustless buckle, the combination with a one-piece wire-frame, having its lower bar bent to form a plurality of depending, upwardly-opening gripping-hooks, of a buckle-lever pivotally mounted
10 upon the upper portion of the buckle-frame, and a piece of webbing having its fixed end inserted into the said hooks which are clamped upon it, and then passed from front to rear over the lower bar of the
15 frame and then downward to form a loop

and then in front of the said hook and over the bend of the fixed end of the webbing, and then under the gripping-edge of the said lever, and then upward from front to rear for deflection by the buckle-lever over ²⁰ the loop formed adjacent to the fixed end of the webbing.

In testimony whereof, I have signed this specification in the presence of two subscribing witnesses.

ROSWELL A. MOORE.
